UNITED STATES PATENT OFFICE.

MAX WURM, OF BROOKLYN, NEW YORK.

EXTENSION-TABLE.

1,154,827.

Specification of Letters Patent. Patented Sept. 28, 1915.

Application filed August 11, 1914. Serial No. 856,276.

To all whom it may concern:

Be it known that I, MAX WURM, a citizen of the United States, residing in Brooklyn, in the county of Kings, State of New York, have invented certain new and useful Improvements in Extension-Tables, of which the following is a specification.

My invention relates to extension tables to which one or more adjustable folding fillers or extension leaves are adjustably attached as a permanent part thereof and which are concealed within the table when folded and placed out of use, and the principal objects of the invention are to provide a folding filler that may be operated in a comparatively shallow space beneath the level of the table-top members and which may be easily adjusted into folded and un-folded position and securely locked in either of said positions, and which may also be readily attached to the ordinary construction of extension table as found on the market, without requiring any especial alteration of the same.

With these and other objects in view my invention consists in the various novel and peculiar arrangements and combinations of the several different parts of the apparatus, all as hereinafter fully set forth and then pointed out in the claims.

I have illustrated a type of my invention in the accompanying drawings, forming part of this specification, and wherein;

Figure 1, is a central vertical sectional view of my improved table, the plane of the section being at right-angles to the abutting edges of the table-top members, and the three folding fillers are shown as folded beneath the table top, out of use. Fig. 2, is a top plan view of the table with the table-top members slid into open position and showing the folded fillers beneath and ready to be unfolded and brought up into place for use, as indicated in Fig. 4. Fig. 3, is a similar view to Fig. 1, but with the central one of the folding fillers adjusted in position of use between the table-top members and with the pedestal broken away. Fig. 4, is a top plan view of the table with the three folding fillers adjusted into position of use between the members of the table-top. Fig. 5, is a cross-sectional view of the upper structure, the plane of the section being indicated by line 5—5, in Fig. 4, and looking in the direc-

tion of the adjacent arrow. Fig. 6, is likewise a cross-sectional view of the upper structure, the plane of the section being indicated by line 6—6, in Fig. 2, and looking in the direction of the adjacent arrow. Figs. 7 and 8, are similar cross-sectional views, the planes of the sections being indicated, respectively, by lines 7—7, Fig. 2, and lines 8—8, Fig. 4. Fig. 9, is a vertical sectional view of the central folding filler shown as about midway of its range of swinging movement.

Referring to the drawings, in which like numbers of reference designate like parts throughout, 1 is a pedestal which is shown as un-divided, though of course an ordinary divided pedestal may be used, if desired, and 2, is the bridge or pedestal-cap which is held in fixed relation to the pedestal and carries at opposite ends the fixed guides or bars 3 and 4, respectively, upon the respective sides of which are slidably mounted the horizontally moving slides 5 and 6, and 7 and 8. To the inner slides 6 and 8, are secured one of the top-members 9, the other top-member 10, being secured to the outer slides 5 and 7, respectively. The inner and abutting edges of the table top members 9 and 10, are provided with dowel pins and corresponding holes 11 and 12, respectively, which co-operate with each other to hold the edges level and prevent sagging at the joint when the two members are placed together, as shown in Fig. 1.

A horizontally arranged spindle or axle 13, is mounted just below the under-side of the top members in suitably spaced longitudinally extending uprights or brackets 14 and 15, respectively, which are secured upon the bridge 2, near the edges thereof, so that the spindle is disposed in the direction in which the top members slide. These brackets 14 and 15, may be made of stout pieces of wood having lateral perforations therein for receiving the spindle with a snug fit, a set-screw 16, being used to hold the spindle fast in its mounting against end-wise movement, as shown in Fig. 2. The spindle is of sufficient length to pass through the two brackets and extend beyond each a distance greater than the width of the folding fillers or leaves 17—18, and 17'—18', respectively, which are swung from the respective ends of the spindle. As the fillers just referred

to are constructed alike, a description of one will serve for the other, which is marked with corresponding reference numerals having a prime mark annexed. The folding 5 filler 17—18, is composed of two sections 17 and 18, which are hinged together transversely at a point near the center of length of the complete filler, by means of a substantial hinge 19, of well known construction and which I prefer to use in order to give a firm bearing to the hinge joint when the two sections are un-folded into the same plane in the position of use. To the under-side of the filler section 17, is secured a 10 plate 20, having perforated lugs 21 and 22, through which the spindle 13, loosely passes and in this way the folding filler is mounted to swing on the spindle on the over-hanging end thereof and eccentric to the hinge-joint. 15 Upon the ends of the spindle are secured stops 23 and 23', respectively, for limiting the lateral sliding movement of the fillers on the spindle, the fillers being permitted to have a certain amount of lateral movement 20 to facilitate adjusting them into position of use and disuse. These fillers are provided on their respective edges with dowel-pins 24, and holes 25, which coöperate with corresponding parts on the abutting edges of 25 the top members or the adjacent filler, as the case may be, and this lends support to the joint between these parts, as shown in Fig. 4. Further support is given the filler when in position of use, by means of a turn-bar 26, which is pivoted at 27, to an upwardly extending projection 28, on the bridge piece 2. See Figs. 5 and 6. This turn-bar also serves to lock the folded filler in position of disuse, as, shown in Figs. 2 30 and 6, wherein it is shown as turned cross-wise and projecting over the folded filler. By turning the bar 26, a quarter of a circle from the position shown in Fig. 2, the folded filler is un-locked ready to be swung 35 up into unfolded position. Beneath the folding filler 17—18, is placed a stop 29, to check the downward movement of the free ends of the folded filler, as shown in Figs. 2 and 6. Except for this stop 29, the space 40 beneath the filler is un-obstructed, so that the hinged end of the folded filler has an open space to swing through when turned on its eccentric axis on the spindle. There is thus provided a simple construction which in no 45 way disfigures the ordinary table structure. The upright in which the spindle 13, is mounted is shown as made in one piece with the extension 28, on which the turn-bar 26, is placed and this single piece is secured to 50 the bridge by means of screws 30, as shown in Fig. 2.

On the under-side of the folding filler 17—18, are fixed pins 31 and 32, which engage with pins 33 and 34, respectively,

upon the inner side of the slides 6 and 8, 65 while similar pins 31' and 32', on the filler 17'—18', engage pins 33' and 34' on the slides 5 and 6, respectively. See Figs. 2 and 6. When the filler is un-folded into the plane of the table top members, the drawing out of such members will cause the pins on the slides to engage the pins on the filler and carry the latter along with the slide. 70

It will be understood that the several parts in the drawings, marked 17' to 34', inclusive, are duplicates of the respective parts marked 17 to 34 inclusive, and which have been hereinabove described, so that it is not necessary to again describe said parts bearing the prime mark. 75

Between the two fillers just described, is arranged a third one composed of two sections 36 and 37, which are secured together transversely by means of a hinge 38. As this filler is located above the bridge and 80 pedestal, I provide means whereby the hinged end of the filler is caused to swing on a very short radius in order to accommodate itself to the shallow confines of this part of the table. This I accomplish by 85 causing the eccentric axis of motion to rise and fall in the swinging operation of the filler. In this arrangement, the distance or radius between the hinge-axis and the eccentric axis on which the folded filler swings, is 90 much shorter than in the other two folding fillers hereinabove described. In the construction shown, the eccentric arbor or axle 95 39, is mounted on the under side of the section 36 of the filler, transversely thereof, by 100 means of a bracket 40, having perforated ears 41 and 42, through which the arbor passes. See Fig. 3. The respective ends of the arbor 39, pass through the arms 43 and 44, of a yoke, the ends of which are pivoted 105 at 45 and 46, respectively, to the extension 28, on the bridge piece 2. See Figs. 2, 3, 7, and 8. The ends of the arbor 39, project beyond the outer faces of the arms of the swinging yoke and when the filler is in unfolded position of use, the said ends rest in notches 47 and 48, respectively, which are formed in the brackets 14 and 15. See Figs. 1, 2 and 8. This serves to support the filler 110 in its extended position and prevent its sagging. When the filler is folded the ends of the arbor likewise take into the notches 47 and 48, and permit the folded parts to be depressed below the level of the table top. 115 At the same time the turn-bar 26, when placed cross-wise acts to support the section 37, of the filler and thus the central filler is 120 firmly held in extended position to maintain itself level with the top members. The sections 36 and 37, of the central filler are 125 provided on their edges with dowel-pins 50 and holes 51, respectively, for coöoperating with the corresponding parts on the ad-

joining filler and top member. See Figs. 2 and 3. These dowel-pins also serve to sustain the filler in secure position when placed between the top members, as shown in Fig. 5 3, or between the end fillers, as shown in Fig. 4.

The central filler is placed in position of use by moving the turn-bars 26, into open position and then grasping the two free ends 10 of the filler-section and raising them. This swings the folded parts on the eccentric axis of arbor 39 and brings the hinged end against the bridge 2, which acting as an abutment or fulcrum for the swinging parts, 15 raises the eccentric arbor on its swinging arms, as shown in Fig. 9, thereby permitting the folded sections to clear the bridge and to be turned over in the shallow space above the bridge. When swung into upright position, the sections are opened out and placed across the slides and then the top members may be slid against the filler, as indicated in Fig. 3, so that the table is extended a distance equal to the width of the 20 filler. If a greater extension of the table is required, the end fillers may be placed in position by sliding back the top members and uncovering the fillers, whereupon they 25 may be released and swung upwardly and unfolded across the slides and the top members pushed against them, as shown in Fig. 4, thereby extending the table the distance 30 of the aggregate width of the three fillers. Before the fillers are unfolded across the 35 slides, the turn-bars 26, are set at right-angles to the length of the fillers and when the latter are unfolded one section thereof is supported thereby, as shown in Figs. 5 and 8, while the other section is supported by 40 the spindle 13. When the fillers at the respective sides of the central one are unfolded into horizontal position and the parts slid together, the edges of the side fillers abut the edges of the central filler and this brings 45 the side fillers directly over the uprights 14, 15, and 28, 28', which then serve to firmly support said fillers in horizontal position. To remove the fillers from position of use 50 and store them in folded position beneath the top members, the latter are drawn apart and this movement first slides the members out of contact with the adjacent fillers so as to release the cooperating dowel pins between said parts. Then the continued movement 55 of said members, causes the pins 33 and 34, on the slides 6 and 8, respectively, to engage the pins 31 and 32, on the under side of the filler 17-18, and to drag the latter sidewise so as to release the dowel-pins between the same and the central-filler. The 60 pins 31' and 32', on the filler 17'-18', are likewise engaged by the pins 33' and 34', on the respective slides 5 and 7, and this serves to move this filler laterally and disengage the

dowel pins between the same and the central-filler. This movement spaces the fillers apart in substantially the manner shown in Fig. 2, whereupon they may be folded up and swung downwardly into the positions shown in Fig. 2, and then locked, after 65 which the top-members may be pushed together and the fillers stored away and concealed, as shown in Fig. 1. In arranging the pins between the slides and the fillers there is sufficient lost motion between them to 70 cause the top-members to space themselves apart before engaging the fillers to draw them away, so that the drawing-out movement of the top-members serves to automatically space them and the fillers from 75 each other and permit the fillers to clear the different parts in folding them and swing- 80 ing them into their lowermost positions.

It will be seen that by virtue of my novel construction, I am enabled to operate the 85 folding fillers in a very shallow space and particularly the central filler which is located over the bridge, and that my improvements may be readily applied to many forms 90 of ordinary tables as found on the market, without making practically any alteration therein. Moreover, there is no depending or projecting part to disfigure the table, as all parts are fully concealed within the ordinary depth of apron 52, which extends 95 around the table top and this is an important advantage in this class of devices.

I wish to be understood as not limiting my invention to the particular construction of the various parts thereof as herewith shown, 100 as it is evident that various modifications may be made in the same, without departing from the spirit of my invention.

Having thus described my invention, what I claim and desire to secure by Letters Patent, is;

1. In a table of the class described, the combination of relatively movable top-members, a folding-filler comprising two sections hinged together with the hinge-axis 110 disposed to one side of the center line of the table when the sections are folded, and swinging-arms mounted to swing on an axis disposed to the other side of said center line and the said sections being pivoted between 115 said swinging-arms with the pivotal axis disposed upon the same side of said center line as said hinge-joint when the filler is folded, substantially as described.

2. In a table of the class described, the 120 combination of relatively movable top-members, a folding-filler comprising two sections hinged together with the hinge-axis disposed to one side of the center line of the table when the sections are folded, and 125 swinging-arms mounted to swing on an axis disposed to the other side of said center line and the said sections being pivoted between

4
said swinging-arms with the pivotal axis disposed upon the same side of said center-line as said hinge-joint when the filler is folded and between said filler hinge-joint 5 and said center-line, substantially as described.

3. In a table of the class described, the combination of relatively movable top-members, a bridge and a spindle mounted transversely above said bridge, a folding-filler 10 mounted on said spindle to one side of the bridge, a central folding-filler mounted above said bridge and comprising two sections hinged together and one of said sections being pivoted on a horizontal axis 15 capable of being raised and lowered to permit said sections to turn in the shallow space above the bridge, the hinged ends of said sections of the central filler being adapted to swing beneath said spindle when the sections 20 are folded, substantially as described.

4. In a table of the class described, the combination of relatively movable top-members, a bridge and supports mounted thereon, a folding-filler mounted above said bridge and comprising two sections hinged together with the hinge-axis disposed to one 25 side of the center-line of the table when the sections are folded, swinging-arms mounted to swing on an axis disposed to the other side of said center-line, and the said folding-filler being pivoted between said swinging-arms with its pivotal axis disposed upon the same side of said center-line as said hinge-joint 30 when the filler is folded, the said swinging-arms being adapted to be supported by said supports when said filler sections are unfolded in horizontal position, substantially as described.

40 5. In a table of the class described, the combination of relatively movable top-members, a bridge and spaced supporting-uprights mounted lengthwise the bridge, swinging-arms pivoted to said supports, a folding-filler mounted above said bridge between 45 said supports and comprising sections hinged together, said swinging-arms being pivotally connected with one of said sections, a spindle mounted on said supports and extending across the bridge and projecting 50 to the outside of each support, a folding-filler mounted on each end of said spindle outside of the support and adapted when unfolded to slide toward said central filler 55 and rest upon the adjacent support, and means for sustaining on said supports the said central filler when the same is unfolded into horizontal position, substantially as described.

60 6. In a table of the class described, the combination of relatively movable top-members, a bridge, a set of folding fillers comprising sections hinged together and mounted to swing on a horizontal axis, and

hand-operated turn-bars mounted above the bridge and serving to hold the fillers in folded depressed position and also to sustain one section of the central filler in horizontal position when unfolded, substantially as described.

7. An extension table provided with relatively movable top-members and a support therefor, a folding filler comprising two sections hinged together, an arbor mounted across the under side of one of said sections with its ends projecting beyond each side thereof, swinging arms pivoted to fixed points and having their other ends pivotally mounted on said arbor, and suitable supports for receiving the respective ends of said arbor when the sections are unfolded and serving to sustain the section bearing the arbor in level position, substantially as described.

8. An extension table provided with relatively movable top-members and a support therefor, a folding filler comprising two sections hinged together, an arbor mounted across the under side of one of said sections with its ends projecting beyond each side thereof, swinging arms pivoted to fixed points and having their other ends mounted to turn on said arbor, suitable supports for receiving the respective ends of said arbor when the sections are un-folded and serving to sustain said section bearing the arbor in level position, and one or more hand-operated turn-bars for sustaining the other said section in level position when unfolded, substantially as described.

9. An extension table provided with relatively movable top-members, a bridge or stretcher and supports mounted thereon for the folding fillers, a folding filler mounted above said bridge, a spindle mounted to project to each side of said filler above the bridge, a folding filler mounted on each projecting end of said spindle and each adapted to rest upon said supports on the bridge when said fillers are unfolded and slid into contact with the filler above the bridge and said top-members, substantially as described.

10. An extension table provided with relatively movable top-members, a bridge or stretcher and supports mounted thereon for the folding fillers, a folding filler mounted above said bridge and comprising two sections hinged together and an arbor mounted across the under side of one section of said filler with its respective ends projecting beyond the sides of the filler, and adapted to rest on said supports to maintain said section level when unfolded, turn-bars mounted on said supports for maintaining the other section of the filler above the bridge level when unfolded, a spindle mounted across said bridge with its respec-

tive ends projecting beyond the sides of said filler above the bridge, a folding filler mounted on each projecting end of said spindle at each side of said central filler and adapted to rest upon said supports so as to maintain the fillers level when unfolded, substantially as described.

In testimony whereof, I have hereunto set my hand in the presence of the two subscribing witnesses.

MAX WURM.
